United States Patent Office

Des. 220,425

Patented Apr. 13, 1971

220,425

SHIPPING CONTAINER

Ralph V. Bardell, Homewood, Ill., assignor to Bennett Industries, Inc., Peotone, Ill.

Filed Jan. 9, 1969, Ser. No. 15,288

Term of patent 14 years

Int. Cl. D9—99

U.S. Cl. D9—216

FIG. 1 is a perspective view of a shipping container showing my new design;

FIG. 2 is a front elevational view thereof, the rear being substantially the same in appearance;

FIG. 3 is a right side elevational view thereof, the left side being substantially the same in appearance;

FIG. 4 is a top plan view thereof; and

FIG. 5 is a bottom plan view thereof.

I claim:

The ornamental design for a shipping container, as shown and described.

UNITED STATES PATENT OFFICE
CERTIFICATE OF CORRECTION

Patent No. Des. 220,425

Dated April 13, 1971

Inventor Ralph V. Bardell

It is certified that error appears in the above-identified patent and that said Letters Patent are hereby corrected as shown below:

After the inventor's name, "assignor to Bennett Industries, Inc., Peotone, Ill." should be --assignor by mesne assignments to Growth International Industries Corp., Cleveland, Ohio--.

Signed and sealed this 14th day of September 1971.
